UNITED STATES PATENT OFFICE

GRAHAM R. SIRWELL, OF BEVERLY HILLS, CALIFORNIA

DESIGN FOR A CONNECTER FOR ELECTRIC WIRES

Application filed May 15, 1929. Serial No. 31,234. Term of patent 7 years.

To all whom it may concern:

Be it known that I, GRAHAM R. SIRWELL, a citizen of the United States of America, residing at Beverly Hills, in the county of Los Angeles and State of California, have invented a certain new, original, and ornamental Design for Connecters for Electric Wires, of which the following is a specification, reference being had to the accompanying drawing, forming part thereof.

In the accompanying drawing,

Figure 1 is a view in side elevation of the connector;

Figure 2 is a view in bottom plan thereof.

The connector consists essentially of a body having one end of narrow annular form and of reduced diameter; an adjoining

smooth surfaced wider annular portion of greatest diameter; a slightly tapered, milled surfaced portion of a greater width immediately adjacent the latter portion and having its greatest diameter substantially equal to that of said annular end portion; and a uniformly tapered, smooth surfaced intermediate portion of greatest width adjoining the milled portion with its greatest diameter less than the smaller diameter of the milled portion; the outer smaller end of this intermediate portion being rounded off.

I claim:

The ornamental design for a connector for electric wires, as shown and described.

GRAHAM R. SIRWELL.
